UNITED STATES PATENT OFFICE.

BENJAMIN J. GREELY, OF BOSTON, MASSACHUSETTS.

BUTTON-HOLE DEVICE FOR SUSPENDERS.

SPECIFICATION forming part of Letters Patent No. 254,956, dated March 14, 1882.

Application filed April 5, 1880. (No model.)

To all whom it may concern:

Be it known that I, BENJAMIN J. GREELY, of Boston, in the county of Suffolk and State of Massachusetts, have invented an Improved 5 Button-Hole Device for Suspenders, of which the following is a full, clear, concise, and exact description, reference being had to the accompanying drawings, forming a part hereof.

My device is composed of a short piece of 10 cord, *a*, the ends of which are brought together and secured by the metal clasp *b*, and this metal clasp *b* is so formed at its upper end as to be readily attached to a cord or suspender-strap, or to a hook, such as is now 15 much used in suspenders.

My invention consists in the short cord *a*, forming the button-hole, the ends of the cord being brought together and encircled and compressed by the parallel tubular portions 1-2 of 20 the clasp *b*, in combination with said clasp *b*, having not only the parallel tubular portions 1-2, but also an attaching portion, 3, by which it may be secured to the suspender.

In the drawings, Figure 1 shows two views 25 of my device adapted to be connected with a cord, *d*, so that the cord can render through the tube on the device. Fig. 2 shows two views of my device with a loop on the clasp *b*, through which a web is passed. The web can 30 render through this loop, as is common in suspenders. Fig. 3 is the same as Fig. 2, except that the web is to be sewed to the loop. In Fig. 4 the loop is smaller than in Figs. 2 and 3, so that the device may be connected 35 with the hooks now much used on suspenders. In Fig. 5 the tubular part of the clasp *b* is arranged differently from the tubular part of the clasp in Fig. 1, in order that the device may be attached to the end of the cord *d*, instead of 40 having that end pass entirely through the tube, as in Fig. 1. Fig. 6 is a perspective view enlarged for clearness. Fig. 7 is a cross-section on line *x* *x*, Fig. 6. Figs. 8, 9, 10, 11, and 12 are plans of the blanks used for the clasps in 45 Figs. 1, 2, 3, 4, and 5.

The clasp is constructed from the blanks shown in Figs. 8, 9, 10, 11, and 12, varying according to the form of clasp desired. These blanks are struck from sheet metal. The parts 1-2 of the blank, which are designed to encircle and compress the ends of the short cord *a*, are pressed into a trough shape. At the same time the part 3 of Fig. 12 is also made trough shape when a clasp like the one shown in Fig. 5 is desired. If the form shown in Fig. 2 is 50 desired, the part 3 of Fig. 9 is pressed around and made to encircle the metallic attaching-loop, and this portion of the clasp is finished. If the form shown in Fig. 1 is desired, the part 3 of Fig. 8 is pressed into tubular form and 55 made ready for the insertion of the cord *d*. The attaching parts of the forms shown in Figs. 3 and 4 are finished when the blanks, Figs. 10 and 11, are struck from the sheet metal. The ends of the short cord are now laid in the 60 trough-shaped parts 1 and 2, and these parts are forced to encircle and compress the ends of the cord, and the teeth which are struck up when the blank is formed are firmly embedded in the ends of the cord, which by the compression of the parts 1 and 2 by the action of 65 the teeth are held firmly in position.

What I claim as my invention is—

The improved button-hole device above described, composed of the short cord *a*, having 70 its ends brought together and each end encircled and compressed by the tubular portions 1-2 of clasp *b*, the clasp *b* being formed of one piece of metal with the two tubular portions 12 to receive and compress the ends of cord *a*, as 75 described, and also with the attaching portion 3, by which the device is attached to the suspender, as set forth.

B. J. GREELY.
